UNITED STATES PATENT OFFICE.

EMIL THEODORE PALMENBERG, OF NEW YORK, N. Y., ASSIGNOR TO J. R. PALMENBERG'S SONS, INC., OF NEW YORK, N. Y., A CORPORATION OF NEW YORK.

DRESS FORM.

Application filed May 5, 1923. Serial No. 636,887.

To all whom it may concern:

Be it known that I, EMIL T. PALMENBERG, a citizen of the United States, and a resident of the city of New York, borough 5 of Manhattan, in the county of New York and State of New York, have invented a new and Improved Dress Form, of which the following is a full, clear, and exact description.

10 This invention relates to dress forms of the type usually employed by makers and vendors of garments, especially feminine apparel, and has reference more particularly to the provision in a dress form simulating 15 a part of the undraped human body, of means associated with that part and serving to retain a garment in place thereon.

An object of the invention is to provide 20 a dress form which may have any desired size or shape, and which simulates a part of the undraped human form and has a surface of smooth texture and simulating the human skin, on which garments, such as light and flimsy dresses for women's 25 wear, may be readily positioned, and which will tend to remain in position particularly with respect to the shoulders of the form.

A further object of the invention is to 30 provide a dress form of the kind described, in which the means for retaining the apparel in position are simple, inconspicuous and effective, and which will not in any way interfere with the ordinary or customary use and function of the dress form.

35 A still further object of the invention is to provide in a dress form garment retaining means which may be inoperatively disposed when not needed or desired.

With these and other objects in view the 40 invention consists in certain novel features of construction, and combinations and arrangements of parts, as will be more fully hereinafter described and pointed out in the claim.

45 The accompanying drawing is a perspective view of a dress form having associated therewith one embodiment of my invention.

Before proceeding to a more detailed explanation of my invention, it should be 50 understood that the particular construction of the dress form per se does not constitute part of the invention, in that the same resides primarily in the association with a dress form of the means for retaining garments or the like in position upon the form. 55 The latter is preferably the type customarily

employed today by dressmakers, modistes and shop keepers, either for use in the constructing of garments or for the displaying of the same for sale. It will be understood that certain of the details of construction of the invention may be varied in accordance with individual preference or necessity without departing from the spirit of the invention.

60 Referring more particularly to the drawing, I have shown a dress form simulating in shape the trunk of a female human form, the upper part 10 approximating the upper part of the trunk and having a neck 11. The 70 waist part 12 and the lower part 13 of the form are covered with suitable fabric. The upper or chest part 10 has a smooth surface, painted or otherwise surfaced, so that it has the appearance and texture of the human 75 skin. This surface is naturally slippery and garments, particularly light and flimsy feminine apparel, when positioned upon the form, would tend to slide from the shoulders. Especially is this true in the 80 case of decollete gowns. The absence of arms also renders more difficult the maintaining in position of such garments.

I provide shoulder straps 14, the extremities 15 of which are glued, sewed, or 85 otherwise suitably attached to and under the upper edge of the fabric covering of the lower part of the form. These straps 14 may be fashioned from any suitable material, such as elastic webbing. They 90 have an outer friction surface which is, of course, considerably rougher than that of the upper part 10 of the form. A garment when placed upon the form, will contact with the shoulder straps, which will thus 95 tend to hold the garment in position, but will not interfere with the easy removal of the garment. Should the straps not be needed or desired, they can be slipped from the shoulders, as is shown at the left hand 100 side of Figure 1, and disposed at the sides of the form.

I claim:

As a new article of manufacture, a dress 105 form having a fabric covering around the body portion of the form, of a pair of shoulder straps secured at their ends to the covering and at their intermediate portions resting on the shoulders of the form, said straps having outer friction surfaces.

EMIL THEODORE PALMENBERG.
